UNITED STATES PATENT OFFICE.

ERNEST A. DE WOLF, OF MANSFIELD, MASSACHUSETTS, ASSIGNOR, BY MESNE ASSIGNMENTS, TO UNIVERSAL WINDING COMPANY, OF BOSTON, MASSACHUSETTS, A CORPORATION OF MASSACHUSETTS.

ELECTRICAL COIL AND METHOD OF WINDING SAME.

1,204,749.

Specification of Letters Patent.

Patented Nov. 14, 1916.

Application filed May 28, 1915. Serial No. 31,032.

To all whom it may concern:

Be it known that I, ERNEST A. DE WOLF, a citizen of the United States, residing at Mansfield, in the county of Bristol, State 5 of Massachusetts, have invented certain new and useful Improvements in Electrical Coils and Methods of Winding Same, of which the following is a specification.

My invention relates to coils for electrical purposes, such as magnet, solenoid, relay, armature, field, reactance and resistance coils, and consists particularly of an improved method of winding the same.

The object of my improvement is to produce a coil with the layers of windings so disposed as to give increased electrical efficiency within a minimum space; to provide for greater stability and prevent displacement of the windings; to reduce the amount 10 of insulation required; to economize in the copper wire or other conducting-material employed; to increase the number of turns within given dimensions; to prevent arcing or short-circuiting between the individual 15 turns and between the layers of windings; to relieve the potential strains between different portions of the windings; and to otherwise enhance the efficiency of the coil both mechanically and electrically, all as 20 set forth more particularly hereinafter.

The invention is fully described in the following specification, illustrated by the accompanying drawings, in which like reference characters designate like parts.

35 In the drawings:—Figure 1 is a view of one form of my improved coil showing it as partly completed; Fig. 2, a sectional view illustrating the arrangement and disposition of the layers of windings in this 40 form of coil; Fig. 3, a sectional view of a modified form of coil in which the same principles of winding are applied in a slightly different manner; and Fig. 4, a 45 part-sectional view of this same form of coil showing a different method of applying insulation between the layers of windings.

Referring first to Figs. 1 and 2, it will be observed that my new method of winding the coil contemplates the novel arrangement of the layers thereof in conoidal or partly conoidal planes, lying in superim-

posed relation and stepped one in advance of another longitudinally of the axis of the coil. In other words, instead of winding 55 the coil in the usual manner with the turns of wire or other conducting-material disposed in cylindrical planes superimposed one directly over the other and concentrically with respect to their common axis, the 60 layers of windings are caused to advance along the axis so that they overlap at the ends and assume a conical form. As the winding continues with the layers progressing axially of the coil, step by step, in conical planes, after the coil reaches a predetermined diameter it grows by longitudinal extension only and this growth can be carried as far as desired without increasing the diameter or the length of the turns in 70 each layer. In this way each succeeding layer is composed of the same number of turns comprising the same length of wire as in each preceding layer and all disposed in uniform relation to the axis of the coil. 75

Figs. 3 and 4 illustrate the most uniform distribution of the turns of wire in the layers of the coil for in this application of my improved system the first or starting layers are laid on a tapered butt or foundation cone formed as a part of the core of the coil. With this arrangement all of the layers are in the form of true cones having the same angle of inclination to the axis of the coil; and hence there will be a uniform 85 length of wire in each layer. In Figs. 1 and 2 the foundation for the ultimate, conical layers is shown as built up by the wire itself which is laid first in a cylindrical layer with the next and subsequent layers overlapping at their forward ends so that gradually the winding assumes a conical form which is continued in the main body of the coil. With either method the principle is the same with all of the layers of the same 90 length and overlapping at their ends so that the coil grows by longitudinal extension with the layers forming an obliquely and progressively laminated structure resembling somewhat the scale formation on 95 the legs of birds. This method of winding in progressive, coniform layers is of course old as applied to the textile art, being extensively used in winding cops and 100

bobbins of filling thread or yarn. As applied to the winding of electrical coils, however, I believe its use to be novel and its advantages are numerous and manifest as

5 will be explained hereinafter.

Specifically, my new system of winding coils according to the present improvement comprises certain steps as follows: Referring particularly to Fig. 2, when the coil 10 is to be built up on a cylindrical core such as the tube or shell S, which may be of paper, fiber or of metal adapted to serve as an armature, the first layer of the windings is laid in cylindrical form concentric 15 with the axis of the core. The length of the layers, or in other words, the length of traverse of the wire-windings, is established in accordance with the number of turns required per layer, and this determines the 20 ultimate diameter of the coil. That is to say, if the windings are deposited on the core or tube S with a relatively long traverse the layers will build up to a greater diameter before assuming the full, conical 25 formation than if the traverse is made shorter. It has before been explained that the coil reaches its maximum diameter when the windings commence to lay in completely conical planes and therefore it will now be 30 obvious that the longer the traverse the greater the diameter of the windings, and hence the ultimate dimensions of the coil can be determined and regulated as desired by simply adjusting the length of the traverse 35 at the start of the coil. The length of traverse of the windings in each layer also determines the angle of inclination of the layers, that is, their degree of taper with respect to the axis of the coil. For this reason 40 it is necessary to establish primarily a length of traverse which will give the proper pitch or taper to the plane of the subsequent layers without tending to cause the wire-windings to slip out of place. This 45 point is a matter which is determined by experiment in accordance with the size or diameter of the wire being wound and other conditions, it being obvious that a comparatively fine wire can be wound more conveniently and the turns will stay in place better on a steeper taper than will a relatively coarse, heavy wire.

In Fig. 2 I have shown the layers of windings as wound with a length of traverse which gives a taper adapted for most varieties of wire employed for electrical purposes, and the resultant coil is of proportions suitable for various uses. In this figure the black sections W represent the layers 60 of wire or other conducting-material in the coil while the white sections X indicate the insulating-material disposed between the wire layers. No attempt is here made to illustrate the individual turns of wire in 65 the different layers as separate and distinct

from each other, but in Figs. 3 and 4 the relation between the adjacent turns or convolutions of the wire is shown more graphically.

In some cases, where the coil is wound 70 from wire which is heavily insulated, as by being covered with silk or cotton wrappings, it is unnecessary to insert additional insulation between the layers. In most instances, however, it is the practice to wind 75 the smaller sizes of coils from enamel-coated wire and this variety of insulation is not so reliable or secure. For this reason I have found it advisable for most coils to provide additional insulation between the separate 80 layers of the wire-windings, and any suitable method may be adopted for this purpose. For instance, the well known practice of inserting strips of paper between the layers can be employed, and, as shown in Fig. 85 2, these strips or sheets X are preferably of slightly greater length than the wire layers in order that they may overlap and protect the end turns of the wire. In Fig. 2 I have shown first a strip or sheet of paper α laid 90 around the tube S and on top of this the first layer w of wire is wound. On top of this another strip of paper α' is laid and around this the second layer of wire w' is wound. This process continues with each 95 succeeding layer of windings stepped slightly forward of the preceding layer and advanced along the axis of the coil. The forward, overlapping portions of the layers will thus be caused to build up in conical 100 form, as shown in Fig. 2, until a point is reached where the last layer w^2 is displaced along the coil entirely beyond the last end 105 of the first layer w . At this juncture the windings in the layer w^2 will be laid wholly in a conical plane and thereafter all of the layers will assume this form while being deposited one over another and slightly in advance of each other longitudinally of 110 the coil. The coil now ceases to increase 115 in diameter, but continues to grow through longitudinal extension and the winding can be carried on indefinitely to attain any desired number of turns or in accordance with the length required.

In the foregoing description I have explained the simplest manner of building the coil with sheets of insulation inserted between its layers. The preferred method of producing coils of this form is, however, 120 by a comparatively new system which has certain advantages particularly applicable to the present invention. This consists in winding cotton yarn or other attenuated textile material of an insulating character 125 into the coil simultaneously with the winding of the wire or other conductor. This new method of building electrical coils is known as the "Leeson-Universal system," and is described in detail in United States 130

Patent No. 1,080,830, granted to Max Helm Dec. 9, 1913. Briefly, it consists in winding the strands of yarn or other textile material crosswise of the turns of wire to weave them in and out through the wire layers and thus link the wire-windings together to bind them in place. This method of building the coil is illustrated in Fig. 1 which shows the turns of wire *w* laid in the conical layers *l* with the usual close, spool-wind, while the strands of yarn *y* are laid in open helices in the cross-wind generally known as the "Universal system." The wire is laid with a relatively slow traverse to deposit the turns in close relation, while the yarn is wound with a much faster traverse so that the convolutions cross each other at sharp angles. The yarn-windings lie diagonally of the wire turns and, weaving in and out through the layers, form a mechanical binder which holds the wire in place and serves as a reinforcing medium for the whole coil. This feature is particularly important with the form of coil herein disclosed because, as will be recognized, it is more difficult to wind on a tapered surface than on a cylindrical one. When winding in a conical plane the turns of wire will have a tendency to slide down the taper and slip out of place, and with the present system of tying the layers in position such displacement can be effectually prevented. Furthermore, the yarn-windings not only serve as a binding and reinforcing means for the wire-windings but they also build up insulation between the layers of the coil. That is to say, the frequent crossing and recrossing of the strands of yarn results in the formation of a protecting covering over each layer of wire and while this does not completely inclose the wire-windings the yarn builds up more thickly at the ends of the wire layers where the potential difference in voltage between layers is greatest and therefore the primary insulation of the wire is reinforced and strengthened at these vulnerable points.

It is the preferred practice to wind the yarn or other insulating-material with a slightly longer traverse than that of the wire and in this way the ends of the wire layers are more thoroughly protected and reinforced. In fact, the overlapping of the yarn-windings at the smaller diameter of the wire layers, that is at the nose of the winding, acts to build up a sort of abutment-ring or collar which holds each layer from slipping down out of place. The overlapping of the yarn-layers at the opposite or butt end of the wire-layers serves to cover the exposed turns of the wire as shown at *b* in Fig. 1, and after the last layer of the coil is finished this can also be protected by continuing the yarn-winding to complete a final covering layer. In this way the

whole coil can be completely armored by a covering of insulating-material without requiring a separate operation of "taping" it, and finally the coil is immersed in shellac, cement, paraffin, liquid "bakelite" or other coating material which solidifies into a hard shell. The windings of yarn which intervene between the wire-windings absorb the cement or other coating medium in such a manner that the whole mass of the coil is thoroughly impregnated and its parts amalgamated so that a particularly staunch and stable structure is secured.

In Figs. 3 and 4 I have illustrated the core *C* on which the coil is wound as formed with a conical head or butt *B*. This provides that the first windings of wire can be disposed in conical planes so that all the layers will have the same number of turns with a uniform length of wire in each layer and all of the layers having the same relation to the axis of the coil. In Fig. 1 the form of the coil is represented by dash lines, and the first few layers are illustrated with the turns of wire shown in section. The first two wire layers are represented at *t* and *t'*, and the overlapping yarn layers are indicated at *y'*, *y''*.

Fig. 4 shows a similar form of coil with the wire layers designated *c*, *c'*, *c''*, etc., and with sheets of insulating-material *p'*, *p''*, *p'''*, etc., inserted therebetween. The last layer of wire *c''* is shown as not quite completed, the wire *w* being illustrated as winding back toward the base end of the coil.

As previously stated it has been demonstrated that many advantages, both electrical and mechanical, result from winding the coil with its turns or convolutions disposed in coniform layers. In the first place, all of the layers can be composed of the same number of turns wound from a uniform length of wire, thus providing for greater uniformity in the resistance factor for all parts of the coil. Another important advantage is that the coil can be wound with a large number of turns without building it up to an excessive diameter, and hence there will be a very considerable saving in wire. Furthermore, the length of the layers of windings can be maintained at the minimum while producing a coil of any length required. In this way the mean length of turn can be kept at a minimum so that the potential strain between the end turns of the layers will be greatly reduced. In addition, the distance from the first layer of the coil to the last layer is greatly extended and thus the potential stress between different sections of the coil is minimized.

Heretofore, when it has been required to produce a coil with a large number of turns or convolutions of wire it has been necessary to build it up in sections which are wound separately and then strung together

on a common core. These sections are wound in the form of relatively thin disks and when placed end for end must be thoroughly insulated one from another. This requires a relatively large amount of insulating material which is not only expensive but also takes up valuable space. With the improved form of coil herein disclosed this separating insulation can be dispensed with 10 so that its cost is saved and a considerable economy in space effected, thus providing for more turns of wire in a coil of given dimensions or, putting it another way, the same number of turns can be wound into a 15 coil occupying much less space. It will also be obvious that the cost of producing a composite coil with the sections wound separately and afterward joined together will be much greater, on account of the extra operations required, than with the present 20 method of winding the coil as a unit completed in one operation.

Still other advantages in the present method of building the coil result from 25 stepping the layers progressively forward, one in advance of another. A much more stable and staunch structure is produced in this way because there will be no tendency for the end turns of the wire to fall down 30 over the ends of the coil or to be otherwise displaced. The stepped relation of the ends of the layers also relieves the potential strain between the end windings and provides against arcing or short-circuiting at 35 these points. For this reason the insulating covering of the wire is less liable to be ruptured and less extra insulation is therefore required at the ends of the layers. It will readily be seen that my improved coil is 40 much stronger in structure than the usual form of coil wound with superimposed cylindrical layers. No heads or flanges are required to hold the windings in place and the overlapping, conical layers act as mutual reinforcement, one for another, much like the buttresses of a building. Besides 45 these physical advantages above pointed out there are also certain electrical advantages accruing from the conoidal form of the layers in my improved coil. For instance, the turns of the wire in each layer are brought closer to the path of greatest density of the 50 magnetic flux, that is nearer to the axis of the coil. It is well known that the electric 55 density on a cylinder with rounded ends is greater at the ends than in the center, and on a cone the density increases as we approach the apex. For this reason the tendency 60 of the current passing through the layers of windings will be to approach the axial center of the coil so that its magnetic efficiency will be much higher than that of the ordinary cylindrically-wound coil. Other advantages of this novel method of 65 producing electrical coils will occur to those

versed in the art and will become apparent from a practical demonstration of its use.

Certain modifications might be made in the form and dimensions of the coil and in the method of producing it without departing from the main principle of the improved system disclosed. Such changes would fall within the spirit and scope of the present invention, and

Therefore without limiting myself to the exact embodiment shown and described what I claim is:—

1. An improved coil for electrical purposes composed of a plurality of overlying layers of convolutions disposed in frusto-conical planes, with all of the layers having a uniform diameter at the base and vertex. 80

2. An improved coil for electrical purposes composed of a plurality of superimposed layers having the turns therein disposed in conical planes advancing progressively along a common axis, with all of the layers of uniform length. 85

3. An improved coil for electrical purposes composed of overlapping layers of uniform length stepped progressively in advance of each other along a common axis with the turns therein disposed in conical planes. 90

4. An improved electrical coil composed of a plurality of superimposed layers of convolutions disposed in conical planes about a common axis with the turns in each layer wound from a uniform length of wire. 95

5. An improved electrical coil composed of a plurality of overlying layers of convolutions disposed in conical planes with all layers comprising a uniform number of turns wound from equal lengths of wire. 100

6. An improved electrical coil composed of a plurality of superimposed layers of convolutions disposed about a common axis with each succeeding layer stepped progressively in advance of the beginning of each preceding layer, and with all of the layers 110 of uniform length.

7. An improved electrical coil composed of a series of coniform layers of convolutions advancing progressively along a common axis with the base ends of the layers forming the cylindrical periphery of the coil, and with all of the layers of uniform length. 115

8. An improved electrical coil composed of a plurality of layers of convolutions, the radii of curvature of which decrease progressively from one end of the layer to the other with the maximum and minimum radii of all the layers substantially uniform, and each layer stepped progressively forward of the preceding layer. 120

9. An improved electrical coil composed of a plurality of layers of convolutions with the radii of curvature of the turns at one end of each layer corresponding with the 130

- diameter of the axial core on which the coil is wound and at the other end with the maximum diameter of the coil.
10. An improved electrical coil composed of a plurality of superimposed layers advancing progressively along a cylindrical core and overlapping each other at their forward ends to build up a structure having opposed frusto-conically shaped ends.
11. An improved electrical coil shaped with oppositely-tapered or conical ends formed by winding the turns of the coil in superimposed, overlapping layers stepped progressively forward along a common axis to build the ultimate layers with the convolutions disposed in conical planes.
12. An improved electrical coil composed of a series of overlapping layers of wire turns of uniform length advancing progressively along a common axis with cross-windings of insulating-material disposed diagonally of the wire-windings and woven in and out through the wire layers to reinforce the structure and secure the wire turns in place.
13. An improved electrical coil composed of a series of coniform layers of wire convolutions of uniform length disposed about a common axis with windings of insulating-material laid cross-wise of the wire-windings and woven in and out through the layers to reinforce the structure and bind the wire turns in place.
14. An improved method of producing electrical coils consisting in winding the wire or other conductor in conical planes advancing progressively along a common axis with all of the layers of uniform length and overlapping each other at their forward ends.
15. An improved method of producing electrical coils consisting in winding the wire or other conductor in layers of uniform length stepped progressively in advance of each other along a common axis so that the layers eventually assume a conical form.
16. An improved method of producing electrical coils consisting in winding the wire or other conductor in superimposed, conical layers of uniform length advancing progressively along a common axis to build up a structure having a cylindrical periphery terminating in a conically-tapered end.
17. An improved method of producing electrical coils consisting in winding conducting-material in superimposed layers of uniform length stepped progressively forward along a common axis to overlap each other at their forward ends and simultaneously winding insulating-material diagonally of the wire-windings to weave it through the layers to reinforce the structure and bind the wire turns in place.
18. An improved method of producing electrical coils consisting in winding the wire or other conductor in superimposed layers of uniform length stepped progressively in advance of each other along the axis of the coil and simultaneously winding strands of insulating-material diagonally of the wire-windings with a longer traverse than that of the wire to bind the wire turns in place and secure them at the ends of the layers.

In testimony whereof I affix my signature in presence of two witnesses.
